ABSTRACT

Needlework involving a loop fabric structure formed by a single thread or strand manipulated in a manner to define loops each of which is knotted to prevent unraveling thereby enabling the material to be cut at any desired point and employed for various purposes.

LOOP FABRIC STRUCTURE

This application is a division of my co-pending application Ser. No. 765,886, filed Oct. 8, 1968 for Attachment Assembly for Loop Construction Fabric now U.S. Pat. No. 3,548,706, issued Dec. 22, 1970.

The present invention generally discloses certain improvements in my prior U.S. Pat. Nos. 2,402,568; 2,407,031 and 2,585,671.

An object of the invention is to provide a loop foundation in which various patterns may be formed by forming knotted loops which may be connected to each other or certain loops surrounded a single point left free and otherwise arranged to provide numerous patterns and designs by using a single strand of material or by employing a plurality of strands of various colors thus facilitating the manufacture of material useful in constructing garments, curtains, tableclothes, bed covers, lace collars, shawls and other material such as hosiery or the like where it is desired to provide a mesh material which will not run or unravel in the event the material is cut.

Another object of the present invention is to provide a loop foundation which is capable of formation by hand by the use of a single straight smooth needle or may be manufactured on a machine similar to a fishnet machine such as disclosed in U.S. Pat. No. 98,461, issued Jan. 4, 1870.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a perspective view of the loop foundation of the present invention incorporated into a hand weaving machine;

FIG. 2 is an enlarged view illustrating the connection of the take-up roller cloth with the material;

FIG. 3 is a plan view of the construction of FIGS. 1 and 2; and

FIG. 4 is a plan view of one embodiment of the material formed by employing the loop foundation of the present invention.

Referring now specifically to the drawings, the numeral 10 generally designates a frame on which a plurality of threads or strands 12 are to be worked by weaving, forming knot loops in various patterns or the like with the frame including a pair of spaced side members 14 provided with a notch or the like 16 at one end thereof for removably receiving a roller 18 thereon. Attached to the roller is a flexible cloth 20 which is connected to the strands or threads 12 at one end and connected to the roller 18 at the other end. The cloth 20 is received in a substantially cylindrical flexible and resilient member 22 constructed of paper, plastic, metal or the like having an entrance slit 23 at one edge thereof for enabling passage of the cloth 20. The slit 23 being defined by the resilient edges of the cylindrical tube 22 will frictionally engage the cloth 20 thus retaining tension thereon.

The edge of the cloth 20 is provided with a plurality of loops 24 thereon which receive a transversely extending connecting

pin 26 or the like therethrough. The ends of the threads 12 are connected with a pin 26 by loops 28 which are defined by knots 30 or the like with the loops 28 being in alignment with the loops 24 thus connecting the threads 12 to the cloth 20.

5 Removal of the connecting rod or pin 26 is accomplished by longitudinal movement of the pin in either direction. The pin may be provided with detachable end members 32 engaging the top edges of the rails 14 and guiding the pin therealong or the ends of the pin 26 may be straight. Also, in some installations, the connecting pin may be in the form of a flexible thread or web of material sufficient to enable a limited tension to be applied to the threads 12 such as occurs in forming knot loops or the like.

15 The loops 24 are formed in the same manner and connected to the edge of the cloth 20 in the same manner as disclosed in the previously mentioned patents in that a series of knots 34, all being the same, are formed from a single, continuous strand along the edge of the material.

Also, the knot loop 24 may be formed in various patterns 20 such as illustrated in FIG. 4 in which the loops 24 are each knotted to a circular member 26 which is continuous with the loops with certain of the loops being free of connection and other of the loops being connected with adjacent loops 24' by knots 34' thus forming rosettes or other desired patterns such 25 as a star or the like.

The loop foundation may be formed in rows of tightly looped strands in which each strand is knotted where it intersects and each loop is knotted where it intersects with strands or the loop foundation may be made in an open mesh type arrangement having various patterns of loops incorporated therein.

What is claimed as new is:

1. A fabric structure comprising a plurality of generally parallel spaced fabric strands, each of said strands having a 35 plurality of longitudinally spaced knotted base loops formed therein, and a plurality of circumferential loops knotted to the periphery of each base loop, the remote circumferential loops on each base loop including a portion knotted to the portion of the strand between adjacent base loops, the center circumferential loop on each base loop being knotted to an adjacent strand thereby securing the strands together to form a mesh material.

2. The structure as defined in claim 1 wherein all of said 45 loops are disposed laterally to the same side of the strand on which they are formed, the center circumferential loop being knotted to the base loops on an adjacent strand whereby all of the loops on all of the strands are in alignment transversely of the strands, all of the circumferential loops except the center one being circumferentially free and oriented and dimensioned so that the circumferential loops adjacent the center one have outer extremities disposed adjacent the adjacent strand and the circumferential loops remote from the center one have outer extremities disposed adjacent the outer extremities of corresponding circumferential loops on adjacent

55 base loops thereby providing a continuous pattern.
